UNITED STATES PATENT OFFICE.

JOHN F. ELLIOTT, OF CINCINNATI, OHIO, ASSIGNOR TO THE SINGER MANUFACTURING COMPANY OF NEW JERSEY.

BLOWER ATTACHMENT FOR SEWING-MACHINES.

SPECIFICATION forming part of Letters Patent No. 423,916, dated March 25, 1890.

Application filed October 16, 1889. Serial No. 327,187. (No model.)

To all whom it may concern:

Be it known that I, JOHN F. ELLIOTT, a citizen of the United States, residing at Cincinnati, in the county of Hamilton and State of Ohio, have invented certain new and useful improvements in Blower Attachments for Sewing-Machines, of which the following is a specification, reference being had therein to the accompanying drawings.

- 10 My invention has for its object to provide a device for making a current of air to blow the lint and dirt out and away from the feed, and from the shuttle-race and shuttle or revolving hook, of a sewing-machine, and thereby avoid the trouble resulting from the clogging of these parts by the lint and dirt which works through the feed and needle openings of the throat-plate. My blower is preferably intermittent in its action, so that 15 20 the blast will not occur at the moments of the formation of the loops of needle-thread to interfere with the proper action of the needle and shuttle, or hook or looper.

In the drawings, Figure 1 is a bottom view 25 of a "Singer" sewing-machine with my invention applied thereto, the shuttle-race and shuttle-driver being removed. Fig. 2 is a detail view to show the relation of the delivery end of the blast-pipe to the throat-plate, and 30 Figs. 3 and 4 are detail views of the blower.

A denotes the oscillating shuttle-driving shaft of a Singer sewing-machine, and B is the blower-casing surrounding said shaft. The casing is provided with a proper opening or openings for the admission of air, and extending from the delivery portion of said casing to the throat-plate is the blast-pipe C, the delivery end of which is adjacent to the throat-plate D, said delivery end of said pipe 35 40 being of a form, as shown, to direct the air against said plate and to the needle and feed openings.

Within the blower-casing B is a fan or wing b, attached to the shaft A and made 45 preferably in the form of a valve, which will close when moving in one direction, but will open on the return movement. This is effected in the present instance by making the wing b in the form of a frame and attaching thereto a thin piece of leather or other material a which is connected at one end or side

to said frame, leaving its other end or side free, said material a thus forming a swinging door. Thus at the forward movement of the fan or wing the door a will lie against the 55 frame of the said fan or wing, but on the return movement it will swing out from said frame, as denoted in Fig. 3, and thus permit the air to pass, so that there will not be an inward suction to the blast-pipe. This provides for an intermittent action of the blast, and the parts will be so arranged and timed that the blast will be suspended at the moments when the needle is throwing out loops to be engaged by the shuttle or hook, and 60 65 thus the proper formation of the loops will not be interfered with.

I do not wish to be understood as limiting myself to all of the details herein shown, as the form of the blower may be varied without departing from the spirit of my invention.

I am aware that sewing-machines having trimming attachments have heretofore been provided with air-forcing devices for blowing away the trimmings, but in all such devices 75 the blast-pipes terminated above the throat-plates, so that instead of preventing dirt and lint from working down through the needle and feed openings into the shuttle-races they had a tendency to force dirt and lint down- 80 85 ward, so that in these instances the shuttle-races were more liable to become clogged than with machines having no blower attachments. In my invention the delivery end of the blast-pipe is beneath the throat-plate adjacent to the needle and feed openings, so that the currents of air pass upward through said openings and effectually prevent dirt and lint from working downward.

I claim—

1. A sewing-machine provided with a blower attachment having a blast-pipe extending to and opening beneath the under side of the throat-plate with its delivery end adjacent to the feed and needle openings 95 thereof, whereby currents of air will be caused to ascend through the said openings and thereby prevent lint and dirt from passing downward through the same to clog the shuttle-race.

2. In a sewing-machine, the combination, with a shaft beneath the work-plate, of a

blower-casing surrounding the said shaft, a fan or wing arranged in said casing and attached to said shaft, and a blast-pipe extending from said casing to and opening beneath the underside of the throat-plate with its delivery end adjacent to the feed and needle openings to cause currents of air to pass upward through the latter.

3. In a sewing-machine, the combination, 10 with an oscillating shaft beneath the work-plate, of a blower - casing surrounding said shaft, a fan or wing arranged within said casing and attached to said shaft, said fan or wing having a valve or swinging door *a*, which 15 closes at the forward movements and opens

at the return movements and thereby causes an intermittent blast, and a blast-pipe *C*, extending from said casing to and opening beneath the under side of the throat-plate with its delivery end adjacent to the feed and 20 needle openings, to cause currents of air to pass upward through the latter and thus prevent dirt and lint from falling through the same.

In testimony whereof I affix my signature in presence of two witnesses.

JOHN F. ELLIOTT.
